STEER BAR CONSTRUCTION

George E. Kershaw, Coldwater, Mich., assignor to
 Pratt Manufacturing Company, Coldwater,
 Mich., a corporation of Michigan

Application February 24, 1949, Serial No. 78,147

4 Claims. (Cl. 280—21)

1

The present invention relates to a steerbar construction for a coasting sled and more particularly to such a steerbar construction which provides an unbroken top surface.

Steerbar constructions in use on coasting sleds at the present time frequently employ a link comprising a pair of metal straps or bars extending one over and one under the center of the steerbar and connected perpendicularly thereto. The top strap breaks the top surface of the steerbar and provides a hazard to users who, in the customary manner, run with the sled and then drop on it as they throw it to the ground. The metal strap and any protruding screws, rivets or bolts are so located that they may readily cut or bruise the chin or face of the user.

Some attempts have been made to eliminate this difficulty by connecting the link bar or strap only to the bottom of the steerbar and eliminating the top strap. Screws have been mainly used as the attaching means. This single strap construction provides a construction which is not sufficiently sturdy to withstand the use to which sleds are put.

Therefore, it is a principal object of the present invention to provide a steerbar construction utilizing a pair of spaced steering straps and which has a smooth unbroken top surface.

It is a further object of the present invention to provide a steerbar construction which is both sturdy and simple.

Other objects of this invention will appear in the following description and appended claims, reference being had to the accompanying drawings forming a part of this specification wherein like reference characters designate corresponding parts in the several views.

In the drawings:

Fig. 1 is a top view of a steerbar and link embodying the present invention.

Fig. 2 is a rear view of the steerbar construction shown in Fig. 1.

Fig. 3 is a sectional view taken substantially along the line 3—3 in the direction of the arrows, Fig. 2.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The steerbar construction of the present invention includes the steerbar 10 which is provided with holes 11 adapted to receive a towing or steering line. The steerbar 10 is also provided with a slot 12 which is slightly larger than the strap 13 which is adapted to fit therethrough. A second strap 14 is disposed beneath the steerbar 10. Holes are provided in the straps 13

2

and 14 and in the lower part of the steerbar 10 and are aligned in the assembled position to accommodate the rivets 15.

The rivets are inserted and exploded on the inside of the slot 12 to form the inner heads. The exploded rivets provide a joint which is sturdy and which will stand hard usage. The method of using explosive rivets is well known and a description of such method is not deemed necessary in connection with this application.

Holes 16 and 17 are provided in the strap 13, and holes 18 and 19 are provided in the strap 14. Holes 16 and 18 are aligned and holes 17 and 19 are aligned when the straps 13 and 14 are affixed in position to the steerbar 10. This construction provides means for pivotally attaching each end of the link formed by the straps 13 and 14 to conventional steering constructions.

A particular advantage of the steerbar construction of the present invention is that by having the top bar of the link concealed within the steerbar at its point of attachment, the top surface of the steerbar is left clear. In addition to eliminating a dangerous hazard, this permits ornamentation or decoration to be placed thereon. Decalcomanias which consist of the name or initials of the seller or user may be placed on the plain top surface. Thus the sleds become personalized merchandise. This is a definite and valuable selling feature.

Having thus described my invention, I claim:

1. A steerbar construction for a coasting sled including a steerbar member having a slot extending laterally therethrough, a rigid strap disposed through said slot, a second rigid strap disposed on the bottom of said steerbar member and vertically aligned with the first mentioned strap, and means for fastening said straps and said steerbar member in fixed relation.

2. A steerbar construction as claimed in claim 1 and further characterized in that vertically aligned holes are provided on each end of the rigid straps in order that the said steerbar construction may be pivotally attached to a conventional steering construction.

3. A steerbar construction as claimed in claim 1 and further characterized in that the fastening means comprises exploded rivets which extend through the bottom strap, the steerbar and the upper strap and which are provided with exploded heads within said steerbar slot.

4. A steerbar construction for coasting sleds which includes in fixed relation, a steerbar member having a smooth top surface, and a link comprising an upper rigid strap extending laterally through the said steerbar member and a lower rigid strap located against the bottom of said steerbar member and vertically aligned with the said upper metal strap.

GEORGE E. KERSHAW.
